UNITED STATES PATENT OFFICE

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY

SPLITTING MACHINE

Application filed November 26, 1929, Serial No. 409,968, and in Great Britain December 14, 1928.

This invention relates to splitting machines and is herein illustrated as embodied in a machine of the type disclosed in United States Letters Patent No. 1,757,160, granted May 6, 1930, on an application filed in the name of myself and Frank B. Keall, said machine being particularly adapted to split the heel end of a sole to form a thin flap which, after the sole has been incorporated in a shoe, may be bent down and attached to the breast of a wood heel.

This machine comprises a knife, a support for a blank, a presser roll located close to the knife and adapted to hold the blank firmly against the support at that locality, and means for reciprocating the support so that the blank is first fed to the knife to cause the flap to be formed and is then withdrawn from the knife.

In machines of this general type it is essential that the sole or other blank be placed accurately in position upon the support in order to ensure that the cut produced by the knife shall be of the desired direction and extent. To this end, according to one feature of the invention, there is provided a stop or gage against which the leading end of the blank may be placed, and means for moving the stop out of the path of movement of the blank prior to the movement of the blank to permit the blank to be presented by movement of the work support to the splitting mechanism. In the illustrated machine the stop normally rests upon the work support just in front of the splitting mechanism and is lifted out of the path of the blank before power is applied to the machine to impart movement to the work support.

After the blank has been properly positioned upon the support, it is desirable that it be prevented from movement with respect to the support during the splitting operation. According, therefore, to another feature of the invention there is provided holding means in the form of a roll which is normal-

ly in inoperative position but is moved into engagement with the blank after the blank has been positioned upon the support. In the illustrated machine this roll is normally spaced above the support, and is moved down to press the blank against the support after the stop referred to above has been lifted; and, in order to facilitate the operation of the machine, both the stop and the roll are connected with an operator-controlled member, such as a treadle, in such manner that movement of this member first brings the roll down upon the blank, then lifts the stop, and finally applies power to the machine.

These and other features of the invention including certain details of construction and combinations of parts will be described as embodied in an illustrated machine and pointed out in the appended claims.

Referring now to the accompanying drawings,

Figure 1 is a side elevation, partly in section, of a machine in which the invention is embodied;

Figure 2 is a front elevation of the machine;

Figure 3 is a front elevation of the stop or guide of the machine shown on an enlarged scale;

Figure 4 is a detail view of part of the roll of the splitting mechanism and the mechanism for driving the roll; and

Figure 5 is a side elevation of part of a machine having embodied in it a modified construction.

The illustrative machine comprises a horizontal cam-shaft 1, which carries the various cams of the machine and is driven through a one-revolution clutch (not shown), a horizontal table 2 to support a loose sole or other blank to be operated upon, means in the form of a roll 47 to press the sole against the table at a locality spaced considerably from the knife, a rotatable presser roll 3 to press the sole against the table close

to the knife to define the thickness of the flap to be split, and a flat straight-edged splitting knife 4.

The front portion of the frame of the machine is provided with a horizontal dovetailed guideway in which is mounted a table-slide 5 having fixed to it the horizontal table or support 2, the top of the table being provided with teeth (not shown) which prevent the work from slipping. The table is adapted to be reciprocated horizontally parallel to the plane of the edge of the splitting knife 4. Motion is given to the table 2 by a pin 6 carried by the table-slide 5 connected by a link 7 with the top end of an upright rocking lever 8, which is pivoted to the frame of the machine and to which rocking motion is imparted by a cam (not shown) on the cam-shaft 1 through a cam-roll 9 carried by a bell-crank lever 10 pivoted at 11 to the machine frame and connected by a link 12 to the lever 8. The arrangement is such that, on the starting of the machine, the table 2 is moved to carry the sole to the splitting knife, and thereafter the table is retracted to initial position to carry the split sole back again clear of the machine instrumentalities.

The knife 4 is fixed to a knife-carrier 13 mounted in a bracket 14, which is carried by the machine frame and is formed at its front end with a head to carry the presser roll 3 which cooperates with the knife. The front of the bracket 14, as has been mentioned, is extended to form a head; at each side of this head is a guideway in which is mounted for up-and-down sliding movement a slider 15 which carries at its lower end a bearing for a trunnion of the roll 3. Each slider 15 has threaded into it a screw 16 which is rotatably mounted in the bracket 14 but prevented from endwise movement therein. Each screw 16 has fixed to its upper end a gear 17 meshing respectively with gears, one of which is shown at 18, said gears being fixed on a shaft 19 rotatably mounted in bearings formed on caps 20 which cover the guideways of the sliders 15. The shaft 19 has fixed on it a handwheel 121 by which it may be rotated to adjust the roll 3 vertically towards or from the knife edge. To indicate the distance of the roll 3 above the knife edge and to assist the operator in adjusting the roll a pointer 21 is pivoted to one of the caps 20 and swings over a scale 22 on the cap when the roll 3 is adjusted. The pointer 21 is connected by a link 23 to a lever 24 pivoted to the cap 20, and the lever 24 has fixed in it a pin 25 which passes through a substantially vertical slot in the cap 20 and into a horizontal slot in the slider 15.

In order to accommodate soles of varying thickness the bracket 14, which carries the splitting knife and the roll 3, is not fixed to the frame of the machine but is pivoted at 26 thereto, and its forward end is yieldingly

urged downward through a spring 27, the effective strength of which may be adjusted by adjusting a collar 28 on a rod 29.

It may be desirable to lift the sole-pressing roll 3 so that it will not press upon the blank when the latter is being withdrawn after the splitting operation has been completed. To this end there is provided an arm 30 projecting rearwardly from the bracket 14 and having its rear end pivotally connected to the rod 29 which passes through a block 31 pivoted to one arm of a two-armed lever 32 pivoted to the machine frame, the other arm of the lever carrying a roll 33 operated by a cam (not shown) on the cam-shaft 1 at the correct time to lift the sole-pressing roll from contact with the work. The forward end of the bracket 14 may be adjusted upwardly or downwardly to adjust the roll 3 and knife 4 relatively to the upper surface of the table 2 by an eccentric sleeve 34 rotatably mounted on the pivot 26 and in the bracket 14. The sleeve 34 has on it an arm 35 which carries a spring plunger 36 arranged to enter any one of a series of holes 37 formed in a segment 38 fixed on the machine frame. By this means the forward end of the bracket may be quickly adjusted and the eccentric sleeve locked in adjusted position.

The roll 3 is preferably rotated so that it assists the table in feeding the work and for this reason one of the trunnions of the roll has fixed on it a pinion 39 (Fig. 4) which meshes with a rack 40 carried by the table. To maintain the rack and pinion always in mesh when the roll 3 rises, the rack is pivoted at 41 to the table, and its rear end is supported by rolls 42, 42 which are carried by an arm 43 pivoted on the trunnion of the roll. Such a driven roll is of particular advantage if it is desired to present to the machine a second time a sole which, during the original operation, has not had its flap formed as long as desired. The driven roll then ensures that the split flap shall be fed to the knife as the table feeds the sole.

In order to hold the work firmly against the work support during the splitting operation, operator-controlled holding means is provided in the form of an auxiliary presser roll 47 which engages the work in advance of the presser roll 3 and knife 4, which constitute the splitting mechanism. Fast to the frame of the machine is a rigid arm or bracket 150 having mounted in it a rock-shaft 143. Fast to this rock-shaft on one side of the bracket 150 is a bell-crank lever 44 having a forwardly projecting arm and an upwardly projecting arm. At the other side of the bracket 150 there is an arm 45 corresponding to the forwardly-projecting arm of the bell-crank lever 44 also fixed on the shaft 143. The front ends of these arms are pivotally connected to the upper end of a floating casting 46, the lower end of which carries the

freely-rotatable clamping or auxiliary pressing roll 47. The upwardly-projecting arm of the bell-crank lever 44 is pulled by a spring 48 in such a direction as to rock the bell-crank 44 so as to raise the casting 46, and with it the auxiliary pressing roll 47, to its highest position, which position is determined by a stop-screw 49 with which the said upwardly-projecting arm of the bell-crank lever 44 is adapted normally to be held by the spring 48. In order to prevent undesired movement of the roll 47 in a direction forwardly and rearwardly during the movement of the blank, a control link 50 is pivotally connected to the casting 46 near its lower end and to the bracket 14 or a part carried thereby. The effective length of the control link 50 is made adjustable in order that the position of the lower end of the casting, and therefore of the roll 47, may be adjusted forwardly and rearwardly of the machine. The upper end of the casting is provided with a vertical recess in which there is mounted a vertically-movable plunger 51, normally pressed upwardly by a spring (not shown) located in the bottom of the recess. Pivoted at 52 to the rigid arm 150 of the machine is a bell-crank lever 53 one arm 54 of which extends forwardly and engages the top of the plunger 51. The other arm 55 of the bell-crank lever 53 has connected to it one end of a rod 56 the other end of which is connected to a bell-crank lever 57 pivoted at 58 to the arm 150. The bell-crank lever 57 is connected by a rod 59 to a lever 60 fixed on a pivot 61 rotatably mounted in the frame of the machine and connected by a rod 62 to a treadle (not shown). Also fixed on the pivot 61 is an arm 63 having connected to it a clutch actuating rod 64. The first part of the downward movement of the treadle moves the roll 47 into engagement with the work on the table 2 and further downward movement of the treadle depresses the plunger 51 in the casting 46 and also, through the rod 64, actuates the clutch to start the machine.

In order that the sole may be positioned readily in correct position longitudinally with respect to the splitting-knife the following device is provided. Near the lower end of the floating casting 46 (Figure 1) there is carried a sole-stop 70 which is adapted to move upwardly and downwardly, being normally held downwardly in contact with the table of the machine so that if a sole, in being positioned in the machine, is moved rearwardly on the table its rear end is stopped as soon as it comes into contact with this sole-stop. The sole-stop 70 is supported as follows:—The sole-stop 70 is supported by two pairs of substantially parallel arms 71, 72 pivoted to the casting 46, the arm 72 being pivoted to the upper end of the stop 70 and the arm 71 to the middle thereof. One of

the arms 72 has projecting from it an arm 73 which is connected by a link 74 to an arm 75 pivoted to the stationary arm 150. The arm 75 is connected by a link 76 to the arm 54 of the lever 53. When the lever 53 is swung forwardly about its pivot by its connections to the treadle, it first pushes down the casting 46 without compressing the spring of the plunger, the sole-stop 70 during this movement of the casting resting on the table 2; and the arms 71, 72 pivoting about their connections to the sole-stop. After the roll 47 engages the sole on the table, further forward movement of the lever 53 depresses the plunger 51 and compresses the plunger spring. During this latter movement of the lever 53 the arm 75 is pressed down by the link 76 and through the link 74 raises the arms 72, 71 and thereby raises the stop 70; and during this latter movement of the lever 53, as has been explained, the clutch is tripped to start the machine. The operator holds the treadle down during the splitting operation.

A modified form of mechanism for depressing the casting 146 (which corresponds to the casting 46) and roll 47 is shown in Figure 5 and comprises a forked hand-lever 65 which is pivoted by its fork at 66 to a forked bracket 67 that extends rearwardly and upwardly from the top of the floating casting 146, the front of the fork of the lever 65 resting upon the top of a plunger 151. The lever 65 projects forwardly into a position in which it may be grasped by the operator. The arrangement is such that normally the floating casting 146 (and therefore the roll 47) is held upwardly clear of the work by the spring 48 of the bell-crank lever 144. After the work has been placed in the machine, the operator grasps the hand-lever 65 and presses downwardly, with the result that he first depresses the plunger 151 and the floating casting 146 as a whole against the spring 48 of the bell-crank lever 44 until the roll 47 contacts with the work; on further depression of the hand-lever 65 the plunger 151 yields downwardly in the floating casting so that, although the casting itself is not depressed further, the pressure on the roll 47 increases as the plunger is depressed downwardly against its spring into the recess in the floating casting. To limit the upward movement of the hand-lever 65 and plunger 151 and to prevent chattering of the hand-lever on the plunger, the hand-lever has a depending lug 68 which carries a roll 69 arranged to underlie and contact with the forked bracket 67 of the floating casting 146 so that the hand-lever is always held in contact with the top of the spring-pressed plunger.

The floating casting 146 near its upper end carries a transverse spindle 77 to which is fixed a rearwardly-projecting arm 78 and a

forwardly-projecting arm 79, the forward end of the latter being connected by a link 80 through a lost-motion connection to the aforementioned hand-lever 65, and the rear end of the rearwardly-projecting arm 78 being pivoted to the top end of the sole-stop 170; the middle of the sole-stop is pivotally connected by a link 81 with the lower part of the floating casting. The arrangement is such that so long as the hand-lever 65 does not move relatively to the floating casting the sole-stop remains in operative position, but when (after the roll 47 has clamped the work) the plunger 151 yields and the hand-lever moves down relatively to the casting, then the spindle 77 is rocked and the sole-stop is raised to a position clear of the work. By adjusting the length of the aforementioned floating-casting control link 50, the position of the sole-stop forwardly and rearwardly in the machine may be adjusted with a consequent adjustment of the position of the rear end of the sole in relation to the splitting knife and a corresponding alteration in the length of sole that is split.

The hand-lever may also be used to apply power to the machine if desired. For instance, the aforementioned transverse spindle 77 may be provided with a third arm 82, which may be connected by a link 83 to a rocking lever 84, which in turn may be connected by another link 85 to the clutch mechanism, the arrangement being such that the clutch is tripped by continued movement of the hand-lever after the sole-stop has been raised from the table.

The operation of this modified form is as follows:—The sole is placed on the table 2 and is moved rearwardly until its rear end contacts with and is stopped by the sole-stop 170, which has been adjusted forwardly and rearwardly by adjustment of the length of the floating-casting control link 50. The operator grasps the hand-lever 65 and depresses it; first the floating casting 146 is depressed until the roll 47 contacts with and presses the sole against the table; further depression of the hand-lever causes the sole-stop 170 to rise to clear the sole; still further depression of the hand-lever causes the clutch to be tripped; and the machine starts and operates as already described. The operator holds the hand-lever depressed so as to clamp the sole to the table throughout the operation.

Although the invention has been set forth as embodied in a particular machine, it should be understood that the invention is not limited in the scope of its application to the particular machine which has been shown and described.

The machine shown in the prior patent, which has been referred to above, is similar in many respects to the present machine, and all subject-matter common to the two machines is claimed in the prior patent.

Having thus described my invention, what I claim as new and desire to secure by Letters Patent of the United States is:

1. A machine of the class described having, in combination, a knife, a support for a blank, means for causing relative movement between the knife and the support to cause the knife to operate upon the blank, and a stop for engaging the end of the blank nearest to the knife for facilitating positioning of the blank upon the support, said stop being movable out of contact with the blank prior to said relative movement between the knife and the support. 70

2. A machine of the class described having, in combination, a knife, a support movable to present a blank to the knife, a stop for engaging the leading end of the blank to facilitate positioning it upon the support, and means for moving the stop out of the path of movement of the blank before movement is imparted to the support. 80

3. A machine of the class described having, in combination, a knife, a support movable to present a blank to the knife, a stop normally resting upon the support for facilitating the positioning of the blank upon the support, and means for raising the stop out of the path of movement of the blank before movement is imparted to the support. 90

4. A machine of the class described having, in combination, splitting mechanism, a normally stationary support movable to present a blank to said mechanism, means movable into a position to hold the blank against the support, a stop for engaging the leading end of the blank to facilitate positioning it upon the support, and means acting first to move the holding means into operative position and then to move the stop out of the path of movement of the blank. 100

5. A machine of the class described having, in combination, a knife, a support movable to present a blank to the knife, a presser adapted to engage the blank at a locality adjacent to the knife, a member adapted to engage the blank in advance of the presser to hold the blank upon the support, said member being normally raised above a blank placed upon the support, a stop normally located in the path of movement of the blank, and means for moving the holding member into contact with the blank and for moving the stop out of the path of movement of the blank. 110

6. A machine of the class described having, in combination, a knife, a support movable to present a blank to the knife, a presser adapted to engage the blank at a locality adjacent to the knife, a member adapted to engage the blank in advance of the presser to hold the blank upon the support, said member being normally raised above a blank placed upon the support, a stop normally located in the path of movement of the blank, 120

130

and a single member manipulation of which first moves the holding member into contact with the blank and then moves the stop out of the path of movement of the blank.

7. A machine of the class described having, in combination, a knife, a support movable to present a blank to the knife, a presser adapted to engage the blank at a locality adjacent to the knife, a member adapted to engage the blank in advance of the presser to hold the blank upon the support, said member being normally raised above a blank placed upon the support, a stop normally located in the path of movement of the blank, and a single member manipulation of which moves the holding member into contact with the blank, moves the stop out of the path of movement of the blank and applies power to the machine.

8. A machine of the class described having, in combination, a splitting mechanism, a support for a blank, means for moving the support to present the blank to the splitting mechanism, a presser roll of circular cross-section mounted for rotation about its own axis and normally spaced from the support sufficiently to permit the blank to be placed between it and the support, and means for moving the roll to cause it to hold the blank against the support.

9. A machine of the class described having, in combination, splitting mechanism, a support for a blank, means for moving the support to present the blank to the splitting mechanism, a presser roll of circular cross-section mounted for rotation about its own axis and normally spaced from the support sufficiently to permit the blank to be placed between it and the support, and operator-controlled means for moving the roll to cause it to hold the blank against the support.

10. A machine of the class described having, in combination, a knife, a support, means for moving the support to present a blank to the knife, a presser adapted to engage the blank in a locality adjacent to the knife, an auxiliary presser in the form of a roll for engaging the blank in advance of the first-named presser, resilient means for normally holding said roll out of blank-engaging position, and operator-controlled means for moving said roll into blank-engaging position.

11. A machine of the class described having, in combination, a knife, a support movable to present a blank to the knife, a presser roll adapted to engage the blank in a locality adjacent to the knife, an auxiliary presser roll adapted to engage the blank in advance of the first-named presser roll, and operator-controlled means for moving the auxiliary presser roll into operative position.

12. A machine of the class described having, in combination, a knife, a support movable to present a blank to the knife, a presser roll adapted to engage the blank in a locality

adjacent to the knife, an auxiliary presser roll adapted to engage the blank in advance of the first-named presser roll, and operator-controlled means for moving the auxiliary presser roll into and maintaining it in operative position.

13. A machine of the class described having, in combination, a knife, a support, means for reciprocating the support to present a blank to the knife, a presser roll adapted to engage the blank in a locality adjacent to the knife, an auxiliary presser roll adapted to engage the blank in advance of the first-named presser roll, and operator-controlled means for moving the auxiliary presser roll into and maintaining it in operative position.

14. A machine of the class described having, in combination, a knife, a support movable to present a blank to the knife, a presser adapted to engage the blank in a locality adjacent to the knife, an auxiliary presser in the form of a roll adapted to engage the blank in advance of the first-named presser, means normally holding the auxiliary presser roll out of blank-engaging position, and operator-controlled means for causing the auxiliary presser roll to press the blank against the support.

15. A machine of the class described having, in combination, a knife, a support movable to present a blank to the knife, a presser adapted to engage the blank in a locality adjacent to the knife, an auxiliary presser in the form of a roll adapted to engage the blank in advance of the first-named presser, resilient means normally holding the auxiliary presser roll out of blank-engaging position, and manually operated means for causing the auxiliary presser roll yieldingly to press the blank against the support.

16. A machine of the class described having, in combination, a knife, a support movable to present a blank to the knife, a presser roll adapted to engage the blank in a locality adjacent to the knife, an auxiliary presser roll adapted to engage the blank in advance of the first-named presser, means normally holding the auxiliary presser roll out of blank-engaging position, and means for causing the auxiliary presser roll to press the blank against the support.

17. A machine of the class described having, in combination, a knife, a support movable to present a blank to the knife, a presser adapted to engage the blank in a locality adjacent to the knife, an auxiliary presser, a member pivoted to the frame of the machine in which the auxiliary presser is mounted, a spring-supported element carried by the member, and means for engaging the spring-supported element to move the member and the auxiliary presser roll toward the support.

18. A machine of the class described having, in combination, a knife, a support mov-

- able to present a blank to the knife, a presser normally held in spaced relation above the support, a control member, mechanism actuated by said control member for connecting the machine to an independent source to drive the machine, and connections between the control member and the presser such that movement of said control member moves the presser toward the support. 10
19. A machine of the class described having, in combination, a knife, a support movable to present a blank to the knife, a presser normally held in spaced relation above the support, a member movement of which applies power to the machine, and connections between the member and the presser such that movement of said member first moves the presser yieldingly into contact with the blank without applying power to the machine and then upon further movement applies power to the machine. 15
20. A machine of the class described having, in combination, a knife, a support movable to present a blank to the knife, a presser adapted to engage the blank in a locality adjacent to the knife, an auxiliary presser adapted to engage the blank in advance of the first-named presser, a member movement of which applies power to the machine, and connections between said member and the auxiliary presser such that movement of said member forces the auxiliary presser against the blank. 25
21. A machine of the class described having, in combination, a knife, a support movable to present a blank to the knife, a presser normally held spaced above the support, a casting by which said presser is carried, a spring-supported plunger mounted in the casting, an actuator, means for moving the actuator to exert force upon the plunger, and means connected with the actuator-moving means for applying power to the machine. 30
22. A machine of the class described having, in combination, splitting mechanism including a knife and a cooperating presser, a normally stationary support movable to present a blank to the splitting mechanism, a holding member adapted to engage the blank in advance of the splitting mechanism to hold the blank upon the support, and a single operator-controlled member manipulation of which first renders the holding means operative and then applies power to the machine. 35
23. A machine of the class described having, in combination, a knife, a reciprocating support to present a blank to the knife, a presser roll for holding the blank against the support in the locality of the knife, operator-controlled means for moving the presser roll out of blank-engaging position, and means on the support and having a constant operative engagement with said roll for rotating the roll first in one direction and then in the other. 40
24. A machine of the class described having, in combination, a knife, a reciprocating support to present a blank to the knife, a presser roll for holding the blank against the support in the locality of the knife, a rack pivotally mounted upon the support, a cooperating gear associated with the roll, means for holding the rack in engagement with the gear, and means for reciprocating the carrier whereby the roll is rotated. 45
25. A machine of the class described having, in combination, a knife, a reciprocating support to present a blank to the knife, a presser roll for holding the blank against the support in the locality of the knife, a rack pivoted to the support, a cooperating gear connected with the roll, means for reciprocating the support, and means for maintaining the rack and the gear in a predetermined meshing engagement irrespective of rise and fall of the roll. 50
26. A machine of the class described having, in combination, a knife, a support for a blank, means for causing relative movement between the knife and the support to cause the knife to operate upon the blank, and a stop for engaging the end of the blank nearest to the knife for facilitating positioning of the blank upon the support, said stop being mounted for movement out of contact with the blank in a path which is substantially transverse to the direction of said relative movement between the knife and the support. 55
27. A machine of the class described having, in combination, a knife, a support for a blank, means for causing relative movement between the knife and the support to cause the knife to operate upon the blank, a stop for engaging the end of the blank nearest to the knife for facilitating positioning of the blank upon the support, and means for maintaining a fixed distance between the stop and the knife regardless of the position of the support, said means being constructed and arranged to accommodate movement of the stop away from the support. 60
28. A machine of the class described having, in combination, a knife, a support for a blank, means for moving the support to present the blank to the knife, a presser for engaging the blank in advance of the knife, resilient means for normally holding the presser out of blank-engaging position, and operator-controlled means for moving the presser into blank-engaging position. 65
29. A machine of the class described having, in combination, a stationary knife, a support for a blank, means for moving the support to present the blank to the knife, a presser for engaging the blank in advance of the knife, means operable normally to hold the presser out of blank-engaging position, and operator-controlled means for moving the presser into blank-engaging position. 70
